(57) **CLAIM**

The ornamental design for a light, as shown and described.

DESCRIPTION

FIG. 1 is a view of one side of a light that has the design.

FIG. 2 is a view of the opposite side of the light.

FIG. 3 is a view of the side of the light seen on the top side of FIG. 1. The opposite side view is a mirror image below the mount.

FIG. 4 is a view of the front of the light.

FIG. 5 is a view of the back of the light.

FIG. 6 is a perspective view of the light from the front and above, with the front of the light shifted downwardly from the position seen in FIG. 1; and,

FIG. 7 is a perspective view of the light from behind, with the front of the light again shifted downwardly.

The broken line showing of portions of the light is for the purpose of illustrating portions of the light and forms no part of the claimed design.
